TAPING HEAD FOR CABLE INSULATING MACHINES

Carl O. Bruestle, Rahway, N. J., assignor to Syncro Machine Company, Perth Amboy, N. J., a corporation of New Jersey

Original application October 20, 1945, Serial No. 623,542. Divided and this application August 14, 1947, Serial No. 768,635.

4 Claims. (CL. 57—3)

1

This invention relates to improvements in taping heads of the type used on a common form of machine for wrapping tapes around elongated members as, for example, insulating tapes on electric cables.

A broad object of this invention is to provide a simplified construction characterized by a considerable reduction in the weight of the parts thereof and reduction in the cost of manufacturing such machines.

Another object of this invention is to provide a taping head support adapted to receive the taping heads in the form of unitary structures which may be bodily adjusted longitudinally of the path of cable travel.

Another object of this invention is to provide an improved brake band construction for such devices whereby the life thereof is greatly increased.

A further object of this invention is to provide an improved and simplified form of adjustable tape tensioning device for taping heads.

Other and more detailed objects of the invention will be apparent from the following description of the embodiment of the invention illustrated in the attached drawings.

This invention resides substantially in the combination, construction, arrangement and relative location of parts as will be described in detail below.

This application is a division of my copending application Serial No. 623,542, filed October 20, 1945, for "Taping head for cable insulating machine."

In the accompanying drawings—

Figure 1 is a front elevational view of one of the tape heads as viewed from the plane 1—1 of Figure 3;

Figure 2 is a rear elevational view of the mechanism of Figure 1 with the support for the taping head omitted;

Figure 3 is a longitudinal, vertical, central, cross-sectional view through the taping head and support;

Figure 4 is a cross-sectional view taken on the line 4—4 of Figure 5 showing the mechanism for adjusting the tape tension;

Figure 5 is a cross-sectional view of the same device taken on the line 5—5 of Figure 4;

Figure 6 is an enlarged detailed cross-sectional view of the safety stop of the tensioning device.

Specifically in the art of insulating electric cables by applying a plurality of helical wraps of insulating tape in superposed layers, there are employed many forms of a general type of ma-

chine in which the cable is pulled in the direction of its length therethrough. Rotating about the cable on an axis coincident with the cable axis is one or more taping mechanisms each comprising a plurality of taping heads which, as they rotate around the cable, each feed a tape thereto and wrap it therearound. In some of the larger machines it is not unusual to simultaneously apply as many as one hundred tapes. The insulating 5 tapes come in the form of heavy reels which are mounted on the machine and bodily rotate on the axis of the cable as well as revolve on their own centers during the application of the tape. Obviously machines of this type run to large dimensions and are of massive construction with the result that at the high speeds of operation practiced tremendous centrifugal forces are generated. It naturally follows, therefore, that the construction must be massive and strong to withstand 10 these forces.

As a result of these fundamental combinations, these types of wrapping machines have always tended to be heavy and massive. This invention is concerned with mechanism by means of which 15 the tension on the tape during application can be actively controlled and the tape reels brought to a quick stop when the tape breaks or runs out.

The mechanism illustrated in the drawings shows only one taping station although a number 20 of them can be arranged in axial alignment with respect to the cable if desired.

Referring to Figure 3, a portion of the main frame of the machine is indicated at 15. Journalled therein on suitable bearings 16 is a hollow 25 arbor or tubular shaft 10 which is caused to revolve at the proper speeds by means of a suitable power source, not shown. The cable to be taped, as is well understood in this art, is pulled in the direction of its length through the tubular shaft 10 and, in the case of Figure 3, in a direction from left to right. The tapes are applied to the cable in the desired overlapping relation by means 30 of taping heads one of which is generally indicated by the reference numeral 14 in Figures 1 and 3. Mounted on the shaft 10, in this case on the forwardmost end thereof, is a taping head support or saddle 11 which is of generally rectangular configuration and has a central passage of a size 35 so that it may be slipped on the end of the shaft. It is locked on the shaft between seats formed thereon as shown comprising an abutment ring 17 and a threaded ring 18 which is threadedly mounted on the shaft and locked in tightened 40 condition by means of one or more set screws 19.

If desired, the saddle 11 can be further secured in place by means of a suitable key, not shown.

On each of the outer faces of the saddle 11 are formed guide seats 12 in which a complementarily shaped slide 13 will fit in an axial direction. Secured on the saddle 11 (see Figure 3) by means of bolts (not shown) is a standard 20 which has a bore therethrough in which one end of a rod 21 lies. The other end of this rod is threaded and engages a threaded lug 22 on the slide 13. The other end of rod 21 has secured to it a locking collar 21' and has a wrench receiving portion 21a so that when bolts 23 are loosened, the rod 21 can be turned to cause the slide 13 to move on the seat 12 of the saddle 11 in an axial direction either way by reason of its threaded engagement with the lug 22. The parts may then be locked in adjusted position by means of bolts 23. The reason for this adjustment will be referred to later in the description of the operation.

The slide 13 has an elongated slot 24 on each side thereof through which the bolts 23 pass down into the saddle 11. After the above adjustment the bolts 23 are tightened to lock the taping head assembly on the saddle against displacement during operation of the machine. In Figure 3 the taping head is shown at its extreme righthand position and can be advanced to the left upon loosening the bolts 23 by the adjustment described above. In passing it may be mentioned that the ring 18' mounted on the rear end of the saddle 11 and shown insulated therefrom is a slip ring for and electrical control circuit with which this disclosure is not concerned.

Integral with the slide 13 and extending upwardly at right angles thereto is a supporting plate 25 suitably braced, as shown in Figure 3, and having a bearing housing 26 at the upper end thereof. Journalled in this housing in suitable bearings is a shaft 27 on which the taping reel mechanism is mounted. On the lefthand end of this shaft is secured a brake drum 28 the periphery of which is engaged by a suitable brake band 29, one end of which is anchored on the bracket 25 at 31, as shown in Figure 2. The other end of the brake band is flexibly connected to the bifurcated end piece 32 mounted on a longitudinally slidable rod 33. Slidably mounted on this rod is a short rack bar 34 which is guided in its movement by a track forming member 35 (see Figures 2 and 3). The rack bar is loaded by a compression spring 36 lying between it and a pair of lock nuts on the end of the shaft 33. The rack bar engages a segmental gear 37 keyed to the shaft 38.

As shown in Figures 4 and 5, the shaft 38 extends into a housing 43 and has an anchor ring 39 keyed thereon to receive the hooked end 40 of a spiral spring 43. The other, that is the hooked end 41 of this spring, is anchored in an external ring gear 42 which rotates in the closely fitting housing 43. This gear is engaged by a worm 44 journalled in a suitable formation forming part of the housing 43 on a shaft which has a wrench receiving end 45. The ring gear 42 is provided with a pin positioned to engage a stop pin 47 mounted on the housing 43. The housing 43 on its outer face has a window opening 43' through which, as is clear from Figure 10, the side face of the ring gear 42 can be seen and upon which arbitrary tension indicating symbols can be marked.

Turning to Figures 1 and 4, the end 38' of the shaft 38 has secured thereon a lever 49 having an extension 50 on which is mounted an adjust-

able screw positioned to actuate a switch 51 mounted on the plate 25 which switch is provided to control the automatic stopping of the machine, a feature which is no part of this invention.

5 The lever 49 is pivotally connected by a link 52 to a lever 53 which is pivotally mounted on a bearing pin 54 secured on plate 25. The lever 53 has a rearward extension to engage an adjustable stop screw 55. The other end of the lever 53 is provided with a guide roller 56 (see Figures 1 and 3). Also mounted on the plate 25 are a pair of fixed guide rollers 57 and 58. The path of the tape over these rollers is shown in Figure 1 by the symbol T.

15 A swiveling tape guide mechanism generally indicated at 100 is mounted on the plate 25 and although shown in considerable detail is not further referred to here since it is not a part of this invention but is in fact disclosed in United States

20 Patent No. 1,997,689. It includes, however, a guide roller 101 swivelly mounted so that the tape will be properly guided to the cable from the idler 58. As is well known in the art, this guide assembly 100 can be shifted from the position shown

25 in Figure 1 to the other side of the path of travel of the cable so that the tape may be applied thereto in either rotational direction.

The proper tension on the tape can easily be determined from experience and arbitrary data

30 and the tape can be put under that tension by rotating the worm 44 by the application of a suitable tool at 45 so as to properly load the spring 43. The proper loading can be represented by predetermined arbitrary symbols which are

35 marked on the ring gear 42 so that they can move into the viewing window 43'. At this point it may be stated that the stop comprising the pin 46 and the screw 47 (see Figure 5) is merely provided to prevent an unthinking workman from 40 rotating the worm 44 in the wrong direction which if carried too far could damage the spring 48 by forcibly uncoiling it.

The tape is removed from the reel along the path shown in Figure 1 so as to first pass around 45 the fixed idler 57, thence around the idler 56 on the pivot arm 53, and from there around fixed idler 58 to the guide roller 101 of the swivel guide assembly. When the spring 48 is properly tensioned the arm 53 will assume some position 50 similar to that shown in Figure 1 since it is connected to the arm 49 attached to the shaft 38. At this time switch 51 is open or closed depending on the type of switch used and the type of control circuit for the control mechanism which in 55 turn controls the power source for the machine, the object of the mechanism being such that the switch 51 is now in the position where the machine may run under its normal controls.

Also at this time the brake band 29 is released 60 from the drum 28 by reason of the fact that the segmental rack 37 is also secured to the shaft 38 and the tape has rotated the shaft 38 to release the brake band. At this point it may be noted that the arm 30 (see Figure 1) is merely provided 65 to limit outer radial movement of the brake band.

The machine is now ready to run and, of course, as the cable moves through the shaft 10 the taping heads rotate about it to lay the tape on the cable in the proper manner. It might be well 70 to point out at this point that when a tape breaks or runs out the lever 53 is freed and the action of the spring 48 acting through the connected mechanism causes counterclockwise rotation of the arm 53 (see Figure 1) with the result that 75 switch 51 is operated by the set screw on arm 50

to actuate the control mechanism to shut the machine down so that the tape can be repaired or a new roll placed on the empty reel.

This leaves only the brake mechanism to be referred to. When the tape breaks or runs out and the machine is shut down, the brake is automatically applied to stop rotation of the reel assembly which in modern high speed machines may be at a high rotational rate. The braking action is simply accomplished by the action of the segmental gear 37 on the rack 34 under the influence of the coil spring 48 which is released at this time as previously described. Referring to Figure 2, the action of this spring is to cause clockwise rotation of the gear 37 which moves the rack 34 towards the right and carries the rod 33 to the right through the intermediate agency of the spring 36. It will be seen that this causes the brake band 29 to grip the brake drum 28 under the action of spring 48 so as to bring the reel assembly to a quick stop with respect to its rotation on the axis of shaft 21 since the brake drum 28 is attached to this shaft (see Figure 3). Thus by the time the machine comes to a stop the reel is stationary with respect to its axis of rotation. The important feature of construction of the brake mechanism is the arrangement whereby the pull on the brake band exerted by this mechanism is in a tangential direction with respect to the drum 28 so that crystallization and fatigue of the end of the brake band at its point of connection in the yoke 32 is greatly reduced if not entirely prevented. As shown in Figure 2, the end of the brake band has a pivotal mounting in the yoke 32 so that it is insured in its tangential direction for all positions of the mechanism.

From the above description, it will be apparent to those skilled in the art that the subject matter of this invention is capable of modification as to its physical forms without departure from the

essence thereof and I do not, therefore, desire to be limited to the disclosure but rather by the appended claims.

What is claimed is:

- 5 1. In a cable wrapping machine, a taping head including a support, a shaft journaled on said support, a tape reel and a brake drum secured to said shaft, a brake band cooperating with said brake drum and having one end anchored on said support, and means for applying and releasing said brake including a member connected to said band, and means for slidably supporting said member so as to move it in a tangential direction with respect to said drum in applying and releasing the brake, said last means including a spring loaded segmental gear, a slidably mounted rack engaging said gear, and means interconnecting said rack with said member.
- 10 2. In the combination of claim 1, said means interconnecting said rack with said member including a resilient member.
- 15 3. In the combination of claim 1, said last means including a member pivotally connected to the end of the brake band.
- 20 4. In the combination of claim 1, said brake applying means including a spring loaded tensioning arm and means for adjusting the loading of said spring.

CARL O. BRUESTLE.
